UNITED STATES PATENT OFFICE.

FRANK CARSON AND WILLIAM GLENN, OF HOULTON, MAINE.

GAME-COUNTER.

SPECIFICATION forming part of Letters Patent No. 592,927, dated November 2, 1897.

Application filed April 23, 1897. Serial No. 633,448. (No model.)

To all whom it may concern:

Be it known that we, FRANK CARSON and WILLIAM GLENN, citizens of the United States, residing at Houlton, in the county of 5 Aroostook and State of Maine, have invented certain new and useful Improvements in Game-Counters, of which the following is a full and complete specification, such as will enable those skilled in the art to which it app-10 pertains to make and use the same.

This invention relates to game-counters and similar devices; and the object thereof is to provide an improved device of this class which is simple in construction and operation and 15 which may be secured to a table or other support.

The invention is fully disclosed in the following specification, of which the accompanying drawings form a part, in which— 20 Figure 1 is a plan view of our improved game-counter, and Fig. 2 a central transverse section thereof.

In the drawings forming part of this specification the separate parts of our improvement are designated by the same numerals of 25 reference in each of the views, and in the practice of our invention we provide a game-counter which comprises a circular plate 5, which is preferably provided at its opposite 30 sides with arms or projections 6, in which are formed openings 7, by means of which the device may be secured to a table or other support.

The disk or plate 5 is provided concentrically of its upper surface with an upwardly-directed bead 8, which is triangular in form or sharpened at its upper edge and which is provided with a plurality of notches or recesses 9, any desired number of which may 35 be employed. Around the circular bead 8 is a circular space 10, which is divided by radial lines 11 into a plurality of spaces, in each of which is placed one of the numerals from “1” to “20,” inclusive, but these spaces and 40 numerals may also be of any desired number, the only object in this connection being to so form the device that the space in which the numerals are placed will be equal to the notches or recesses 9 in the bead 8 and will 45 be arranged in radial line therewith. The disk or plate 5 is also provided centrally with an upwardly-directed lug or projection 13, to

which is pivoted a pointer 14, which extends outwardly over the spaces 12, in which the numerals are placed, and said pointer is pro- 55 vided with a knob or handle 15.

The operation of the device will be readily understood from the foregoing description when taken in connection with the accompanying drawings and the following statement 60 thereof, and this device is intended for use in counting the points of the game and may be used for counting the games themselves, and for this purpose the pointer is set at the zero-point indicated at 16, and each point of the 65 game or each game is counted by turning the pointer to the right. The pointer is provided on the under side thereof with a tooth or projection 16^a, which is adapted to engage with the notches or recesses 9 in the bead 8, and 70 said pointer is composed of spring metal, and the tooth or projection 16^a is adapted to hold the same in the desired position and to prevent the accidental movement thereof.

This device is simple in construction and 75 operation and comparatively inexpensive, and it will be apparent that changes in and modifications of the construction herein described may be made without departing from the spirit of our invention or sacrificing its ad- 80 vantages.

Having fully described our invention, we claim as new and desire to secure by Letters Patent—

1. In a game-counter of the character described, an annular bead stamped in the base-plate and projecting upwardly, a boss stamped in said base at the central point thereof, a pointer pivotally mounted upon said boss, said bead being provided on the upper surface 90 thereof with a plurality of notches or recesses, and said pointer being provided with a de- pending arm adapted to engage successively said notches or recesses, substantially as and for the purpose described. 85

2. The herein-described game-counter comprising a circular plate 5 provided with arms or projections 6 which are perforated, said plate being also provided concentrically of its upper surface with an upwardly-directed 100 bead 8 which is triangular in form in cross-section and provided with a plurality of notches or recesses 9, a circular space 10 ad- jacent to said bead and divided by radial lines 95

11 into a plurality of spaces each of which is
designated by a numeral, the notches in said
bead being at a central point of the said
spaces, said plate 5 being also provided with
5 a lug or projection 13, a pointer 14 pivotally
mounted thereon and provided with a knob
or handle 15 and with a tooth or projection
16^a, substantially as and for the purpose de-
scribed.

In testimony that we claim the foregoing 10
as our invention we have signed our names,
in presence of the subscribing witnesses, this
17th day of April, 1897.

FRANK CARSON.
WILLIAM GLENN.
